UNITED STATES PATENT OFFICE.

EMIL KELLER, OF VIENNA, AUSTRIA.

FLEXIBLE PAPER TUBING.

1,388,467.

Specification of Letters Patent. Patented Aug. 23, 1921.

Original application filed May 22, 1919, Serial No. 299,056. Divided and this application filed May 1, 1920. Serial No. 378,245.

To all whom it may concern:

Be it known that I, EMIL KELLER, a citizen of the Republic of Austria, residing at Vienna, Austria, have invented certain new and useful Improvements in Flexible Paper Tubing, of which the following is a specification.

My invention relates to flexible paper tubings.

10 This case is a division of my application Serial No. 299,056, filed May 22, 1919.

It has already been proposed to replace caoutchouc tubes by tubes or hose of paper having side walls provided with grooves or 15 corrugations running transversely to the tube axis. The grooves or corrugations of this known type of tubes are however comparatively flat and distant from each other, so that a longitudinal section through the 20 tube will offer the general aspect of a more or less steep sine curve. The flexibility and elasticity of the tube acquired by thus forming it will however be only very small. Besides grooves or corrugations of the form 25 above described will not impart a sufficient force of resistance against strains directed transversely to the tube axis. A high degree of capacity of resistance against lateral strains and a high flexibility are however of 30 primary importance for the practicability of a paper tube, which, unlike the caoutchouc tube, will not return to its original form, when depressed at some place or squashed or flattened at a sudden bend.

35 The object of this invention is such an improvement of the aforementioned known type of paper tubes that they will form a perfect substitute for the india rubber or caoutchouc tubes. The qualities required to 40 attain this object are imparted to the paper tube by arranging transversal grooves or corrugations in such a way that they will closely abut, the sides of said grooves being substantially perpendicular to the tube axis 45 and acting as bracing pieces. By these means the tube acquires an increased elasticity and flexibility as well as the required strength against lateral forces, that have the tendency to depress or flatten its side walls. A further 50 increase of elasticity and flexibility will be obtained according to this invention, by gluing or cementing the paper layers forming the constituent parts of the tube merely at certain places properly distributed along the 55 circumference of the tube.

The invention is illustrated in the accompanying drawing in which—

Figure 1 represents a tube or hose manufactured according to this invention, partly in a side view and partly in a longitudinal section.

Figs. 2 and 3 show the paper layers, when unrolled and spread in a plane.

Fig. 4 represents a cross section through the tube.

The improved tube or hose consists of paper layers 1, the number of which is suitably chosen according to the intended purpose. The layers are tightly wound upon each other on a cylindrical mandrel and the 70 adjoining layers are glued or connected together. The tube thus formed is then provided with grooves or corrugations running along a spiral or helix, the side walls of said corrugations being substantially perpendicular to the tube axis. As shown in Fig. 1 the 75 grooves or corrugations closely abut, so that their crests and hollows are of semi-circular shape, the side parts of the grooves connecting said crests and hollows being substantially perpendicular to the axis of the tube. The said side parts, forming, as it were, a series of closely abutting rings constituting the peripheral walls of the tube or hose, are 80 united to form a single continuous surface by means of the semi-circular crests and hollows, thus imparting to the tube a high resistive capacity against transverse forces 85 working substantially perpendicular to the tube axis.

90 Corrugations or grooves having the form of a sine curve are easily deformable; the side parts of such grooves are comparable to truncated cones, which by a pressure directed vertically to the axis, accept partly the form 95 of a cylinder, and can be pressed inwardly, when the load becomes comparatively high. Such yielding and flattening of the grooves or corrugations is, however, rendered almost impossible, if they are arranged to closely 100 abut in such a way that their side parts will be substantially perpendicular to the tube axis.

Moreover, by means of the closely abutting grooves or corrugations an extraordinary increase of the flexibility and elasticity of the tube is produced. The side parts of the grooves 3, which are of a depth not less than the distance between a crest and an adjacent hollow, being closely abutting and substan- 110

tially perpendicular to the tube axis, a sort of store or reserve of material, as it were, is formed which suffices even in the case of very sudden turns or of ample lengthening or extension of the tube. Even in the case of very sudden bends the tube retains its perfect circular cross section; no depressing or breaking on the inner and no flattening on the outer side will occur, as is the case with ordinary paper tubes having flat and not closely abutting corrugations, which frequently are completely squeezed together at sudden bends of the tube.

A special advantage of the improved paper tube consists in the fact, that the close vicinity of the grooves or corrugations causes the formation of grooves with very small radius of curvature, which facilitate the return into the original shape after a deformation due to some violent influence.

A further increase of the flexibility and elasticity is obtained according to this invention by gluing or cementing the paper layers 1 only at certain places and by distributing these places uniformly along the circumference of the tube. As shown in Figs. 2 and 3, two superposed paper layers are preferably glued or cemented merely along axial or helical strips or at certain places of such a line or curve, and the places glued of the superposed layers are staggered, in order to obtain a uniform distribution along the whole circumference (see Fig. 4). The inner and outer margins of each layer are of course likewise glued or cemented to the adjoining layer.

Gluing or cementing only at intervals allows of a very small displacement of the layers relatively to each other, which will occur, when a pull slightly flattening the grooves or corrugations 3 is caused by bending or stretching the tube. This lateral play of the paper layers, however small, adds greatly to the flexibility and elasticity of the tube.

To increase the impermeability against liquids or gases and the capacity to resist chemical influences, the paper used for the manufacture of the tube may be impregnated with a suitable substance as paraffin, oil varnish or the like. Instead of using a paper sized in the common fashion it is also possible to use a parchment paper or some paper prepared with a sizing rendered insoluble by a treatment with chromic salts.

To increase the capacity of resistance against mechanical influences the tube may be provided with an inlay of wire gauze or other fabric, as is well known with caoutchouc tubes or it may be made of linen paper or muslin paper or may be lined or coated on its inner or outer side or on both sides with such fabrics.

Moreover the tube may be given a lining consisting of a very thin seamless metal

tube, as shown at 4 in Fig. 4, which is grooved and corrugated together with the paper tube.

Paper tubes manufactured according to this invention will have the advantage of being more proof against some chemical influences, and less inclined to become brittle.

If used to contain fluids under pressure, tubes of the above description will be subject to an extension which can however be minimized by loosely slipping over the tube an envelop or coating consisting of a strong but flexible fabric, fastened at the ends of the tube.

What I claim is:

1. As an article of manufacture, a flexible tubing consisting of a paper tube, provided with corrugations having intermediate side parts between their hollows and crests, which are closely abutting along their adjacent faces.

2. As an article of manufacture, a flexible tubing consisting of a paper tube provided with corrugations having intermediate side parts between their hollows and crests which are perpendicular to the tube axis and forming bracing pieces for the side walls of the tube.

3. As an article of manufacture, a flexible tubing consisting of a paper tube provided with corrugations having intermediate side parts between their hollows and crests and of a depth not less than the distance between the hollow and the adjacent crest of a corrugation, said side parts being closely abutting along their adjacent faces, the said corrugations thus forming a reserve of material to be paid out at bends of the tubing.

4. As an article of manufacture, a flexible tubing consisting of a paper tube formed by a series of superposed layers of paper glued together and provided with corrugations having intermediate side parts between their hollows and crests, closely abutting along their adjacent faces.

5. As an article of manufacture, a flexible tubing consisting of a paper tube, formed by a series of superposed layers of paper glued together and provided with corrugations of a depth not less than the distance between the hollow and the adjacent crest of corrugations and having intermediate side parts between their hollows and crests, closely abutting along their adjacent faces, to form a reserve of material to be paid out at bends of the tubing.

6. As an article of manufacture, a flexible tubing consisting of a paper tube formed by a series of superposed layers of paper glued together at places distributed along the circumference of the tube and provided with corrugations having intermediate side parts between their hollows and crests closely abutting along their adjacent faces.

7. As an article of manufacture, a flexible tubing consisting of a paper tube provided with corrugations running along a helical line and having intermediate side parts between their hollows and crests which are closely abutting, the pitch of said helix being of such width that close abutment is obtained along the outer and the inner faces of the corrugations of the tube.
8. As an article of manufacture, a flexible tubing, consisting of a paper tube formed by a series of superposed layers of paper glued together at places distributed along the circumference of the tube, the said tube being provided with corrugations running along a helical line and having intermediate side parts between their hollows and crests, which are closely abutting, the pitch of said helix being of such width that close abutment is obtained along the outer and the inner faces of the corrugations of the tube.
9. As an article of manufacture, a flexible tubing consisting of a paper tube formed by a series of superposed layers of paper glued together at places distributed along a helical line along the circumference of the tube the said tube being provided with corrugations running along a helical line and having intermediate side parts between their hollows and crests, which are closely abutting along the outer and inner faces of the corrugations.
10. As an article of manufacture, a flexible tubing consisting of a paper tube formed by a series of superposed layers of paper glued together at places distributed along the circumference of the tube, the gluing places in the superposed layers being staggered, the said tube being provided with corrugations running along a helical line and having intermediate side parts between their hollows and crests which are closely abutting along the outer and inner faces of the corrugations.

In testimony whereof I have affixed my signature.

EMIL KELLER.
